UNITED STATES PATENT OFFICE.

ANGEL STATHAKIS, OF ELIZABETH, NEW JERSEY, ASSIGNOR OF ONE-HALF TO THOMAS F. BURKE, OF ELIZABETH, NEW JERSEY.

CARPET-CLEANER.

1,244,139.

Specification of Letters Patent. Patented Oct. 23, 1917.

Application filed March 30, 1914. Serial No. 828,163.

To all whom it may concern:

Be it known that I, ANGEL STATHAKIS, a citizen of the United States, and residing at Elizabeth, in the county of Union and State of New Jersey, have invented certain new and useful Improvements in Carpet-Cleaners, of which the following is a specification, such as will enable those skilled in the art to which it appertains to make and use the same.

This invention relates to carpet cleaners, and the object thereof is to provide an improved sanitary device of this class which will not produce dust and which will also act as a germ and insect destroyer.

The invention is fully disclosed in the following specification, of which the accompanying drawings form a part, in which the separate parts of my improvement are designated by suitable reference characters in each of the views, and in which;

Figure 1 is a side view of my improved carpet cleaner;

Fig. 2 a plan view with the cover at one end portion thereof, removed;

Fig. 3 a transverse section on the line 3—3 of Fig. 2;

Fig. 4 a central longitudinal section on the line 4—4 of Fig. 2;

Fig. 5 a sectional detail of a part of the construction shown in Fig. 4, detached, and on an enlarged scale;

Fig. 6 a view similar to Fig. 4, but showing only a part of the construction and showing the same on an enlarged scale;

Fig. 7 a section on the line 7—7 of Fig. 4, and;

Fig. 8 a section on the line 8—8 of Fig. 4.

In the practice of my invention, I provide an oblong box-shaped body *a*, in the sides of which are pivoted in the usual manner, a yoke-shaped handle attachment *a*² which extends rearwardly and is provided with a handle *a*³ whereby the carpet cleaner may be manipulated.

The front end portion of the body *a* is divided by a transverse partition *a*⁵ into a front compartment *a*⁶ and a rear compartment *a*⁷, and the rear compartment *a*⁷ is of

about twice the dimensions of the front compartments *a*⁶, in the form of construction shown, and said body is provided with a transverse front end wall *a*⁸ which forms the front end wall of the compartment *a*⁶,

and which is shown in transverse section 55 in Fig. 7.

The bottom of the transverse front end wall *a*⁸ is provided with a downward extension *a*⁹ in the bottom of which is a triangular transverse chamber *b*, the apex of which is provided with a central bore or passage *b*² which extends upwardly through said front end wall, and the upper end portion of which is enlarged, as shown at *b*³, and the chamber *b* opens downwardly through the downward extension *a*⁹ of said end wall and forms a transverse mouth or inlet having front and back lips *b*⁴ and *b*⁵ which bear on the carpet in the operation of the machine.

The transverse partition wall *a*⁵ is provided with a central bore or passage *c*, clearly shown in Figs. 6 and 8, and which extends downwardly from the top thereof to about the middle thereof where it communicates with a transverse chamber *c*², and the upper end of the bore or passage *c*, is enlarged, as shown at *c*³, and said bore or passage is also provided above the chamber *c*² with a port *c*⁴ which opens rearwardly through the said transverse partition wall *a*⁵, and the transverse chamber *c*² is provided at its opposite ends with similar ports *c*⁵ which also open rearwardly through said partition wall.

The port *c*⁴ is provided with a flexible valve *d* secured below said port, as shown at *d*² in Figs. 4 and 6, and the upper end of said valve is provided with fine spiral springs *d*³ which are secured to the partition *a*⁵ and which normally hold the valve *d* closed.

The valve *d* is secured to the rear of the partition *a*⁵ and opens into a bellows device *d*⁴ having a rear board *d*⁵ hinged at the bottom thereof, as shown at *d*⁶, and said board *d*⁵ of the bellows device *d*⁴ is provided centrally with a port *d*⁷ closed by a flexible valve *d*⁸ secured below said port, as shown at *d*⁹, and the top of which is provided with small spiral springs *d*¹⁰ which are secured to the board *d*⁵ and which normally hold the valve *d*⁸ closed.

The ports or passages *c*⁵ at the ends of the transverse chamber *c*² in the partition *a*⁵ also open rearwardly through said partition and into bellows devices *d*¹¹ at the opposite sides of the bellows device *d*⁴ and ex-

actly similar in construction to said bellows device d^4 , except that the position of the bellows devices d^{11} is the reverse of that of the bellows device d^4 , as clearly shown. In order to economize space, transversely of the apparatus, and to make the bellows devices d^4 and d^{11} of as great capacity as possible, said bellows devices are made wider at one end than the other, as shown in Figs. 2 and 3, and the wider end of the bellows device d^4 is directed upwardly, while the wider ends of the bellows devices d^{11} are directed downwardly.

Mounted transversely in the bottom of the rear portion of the body a is a crank shaft or axle e , the ends of which extend through the sides of the body a and are provided with wheels e^2 which are inclosed, or partially inclosed, in housings e^3 in the opposite sides of said body portion, and the bottoms of the wheels e^2 are substantially in the same horizontal plane as the bottom of the downward extension a^9 of the front wall a^8 of said body.

The crank shaft e is provided with a central crank e^4 on the opposite sides of which are other cranks e^5 , and the cranks e^5 are provided with connecting rods e^6 which are connected with the bottoms of the rear boards of the bellows devices d^{11} .

The crank e^4 is provided with a connecting rod e^7 which is connected with a link e^8 mounted on a support e^9 arranged transversely of the rear portion of the body a and with the upper end of which is connected a link member e^{10} which is connected with the top of the rear board d^5 of the bellows d^4 .

Placed in the front compartment a^6 is a removable receptacle f preferably composed of glass and provided centrally of the top thereof with a tubular neck f^2 , and I also provide a yoke-shaped conveying device g composed of tubular side arms g^2 and g^3 connected to form a central downwardly directed shank member g^4 having two passage ways g^5 and g^6 which communicate respectively with the tubular side arms g^2 and g^3 and mounted on the shank g^4 is a tapered sleeve or plug g^7 adapted to enter and close the neck f^2 of the receptacle f , when the conveying device g is inserted into position for use, as shown in Fig. 4.

The passage way g^5 which communicates with the arm g^2 of the conveying device g is extended downwardly below the passage way g^6 , as shown at g^8 , so that when said device is in position the passage way g^5 will extend downwardly into the bottom portion of the receptacle f , while the passage way g^6 terminates in the neck portion f^2 of said receptacle, and the tube having the passage way g^5 is provided below the bottom of the passage way g^6 with a radial baffle g^9 for preventing any dust or the like passing into the passage g^5 .

In order that the conveying device g may be placed in proper position for use, by any one using the apparatus, and as shown in Fig. 3, the side arm g^2 is made longer than the side arm g^3 , and any one using the apparatus will understand that the side arm g^2 is the front arm of said conveying device, and the arm g^3 the rear arm thereof, and this will enable the operator to place the device in proper position.

The body a is preferably provided around the sides and front end thereof with a flexible buffer h , and the crank shaft or axle e is preferably inclosed by a housing i of sheet metal or other suitable material secured to the bottom of said body, or forming a part thereof, or said housing may form the entire bottom of the chamber a^7 if desired.

The chamber a^7 is also preferably provided with a cover j which may be secured in position in any desired manner, and both the cover j and housing i may be detachable.

In the use of this device or apparatus, the receptacle f is partially filled with water, as shown at k , before it is placed in position, after which the yoke-shaped conveying device g is inserted, as shown in Fig. 4, the part g^8 extending downwardly through the neck f^2 of the receptacle f and into the bottom portion of said receptacle, while the front and back arms g^2 and g^3 of said conveying device are inserted into the enlarged upper ends of the passages b^2 and c in the front wall a^8 and partition a^5 , as shown at m , which enlarged portions of said passages are packed, as clearly shown in Fig. 4, to make the same airtight, and when the parts are thus assembled, the device is moved around over the carpet to be cleaned either forwardly or backwardly, by means of the handle attachment a^2 .

In this operation, there is a strong suction of air produced, up through the passage b^2 and through the front arm g^2 of the yoke-shaped conveying device g and down through the tubular passage g^5 into the bottom of the receptacle f , and this air, after passing through the water is drawn through the arm g^8 of the conveying device g and through the bellows devices d^4 and d^{11} , and discharged in a purified condition into the compartment a^7 , from which it may be discharged through an aperture n in the back wall of said compartment. In this operation, all dust, fine dirt, microbes, or small insects, that may be in the carpet are taken up and deposited in the water in the bottom of the receptacle f , and after the operation of cleaning the carpet has been completed, the yoke-shaped conveying device g is detached and the receptacle f taken out and cleaned, or the contents thereof discharged.

In the above described operation, the lip members b^4 and b^5 bear on the carpet and

loosen up the dust, dirt, and other substances therein so as to permit the same to be drawn up through the chamber *b* and passage way *b*².

- 5 The receptacle *f* is preferably made of transparent material, in order that the condition of the water *k* in the operation of the cleaner may be seen, but said receptacle may be made of any preferred material, and
 10 changes in and modifications of the various elements of my improved carpet cleaning device, as herein shown and described may be made, within the scope of the appended claims, without departing from the spirit of
 15 my invention or sacrificing its advantages.

Although I have described my invention as particularly designed for use in cleaning carpets, it will be understood that it is not limited to such use, and may be employed in
 20 cleaning bare floors, or floors provided with other coverings, and it may also be used in cleaning many other surfaces or articles.

Having fully described my invention, what I claim as new and desire to secure by
 25 Letters Patent is;—

1. In a dust collector, a frame provided with an air inlet passage and an air outlet passage, a separating receptacle located in said frame and adapted to contain a cleaning liquid, an integral rigid conveying member provided with a freely removable closure for said receptacle and consisting of a long leg which extends into said receptacle to a point beneath the surface of the liquid and
 30 a short leg which extends into said recepta-
 35

cle to a point above said liquid, a curved tubular arm forming a continuation of said long leg and the free end of which rests in said air inlet passage, another curved tubular arm forming a continuation of the short 40 leg and having its free end resting in said air outlet passage and a suction device connected to the air outlet passage.

2. In a dust collector, a removable separating receptacle adapted to contain a cleaning liquid and provided with a neck, an integral removable conveying member consisting of two different length legs extending into said receptacle and provided with a freely removable closure for said neck, a 45 baffle provided on the leg of greatest length below the lower end of the leg of least length for preventing dust or the like entering the leg of least length, a curved rigid inlet arm forming a continuation of said long leg 50 through which dust laden air is adapted to be drawn, a curved rigid outlet arm forming a continuation of the short leg through which cleaned air is adapted to be drawn, and a suction device connected to the outlet 55 arm.

In testimony that I claim the foregoing as my invention I have signed my name in presence of the subscribing witnesses this 28th day of March 1914.

ANGEL STATHAKIS.
